SLICING DEVICE WITH REMOVABLE CUTTING ELEMENT

B. Leonard Polkosnik, Bridgeport, Conn., assignor to Damar Products, Inc., Newark, N. J., a corporation of New Jersey

Application March 27, 1952, Serial No. 278,908

1 Claim. (Cl. 146—169)

My invention relates to an improvement in vegetable cutting devices, wherein a grid-like cutting element is mounted transversely on a base, and wherein means are provided for pushing a vegetable on said base against said cutting element in order to slice the vegetable. In particular, my invention relates to improved mounting means for the cutting element, whereby it may be readily disassembled and replaced by an element in which the openings are of a different size.

I provide the base with side walls which serve as guide means for a longitudinally slidable, transverse pusher plate which may be actuated to push a vegetable toward the front of the base. I mount two parallel transverse and longitudinal plates on the front of the base, and I provide a lateral rod which extends through suitable openings in these plates. This rod serves a dual purpose. Its end portions outside the plates serve as respective mounting means for drive levers which are coupled to the pusher plate. In addition, the rod serves as a support for the cutting element.

The cutting element is provided at its upper end with a pair of hooks which rest upon the rod and normally substantially prevent longitudinal movement of the upper portion of the element. Normally, the lower portion of the cutting element extends in front of and below the front edge of the base, and the plates supporting the rod have flanges which prevent forward removal of the element. However, the hooks are constructed in such a way that the element may be raised upwardly, and then the upper portion thereof may be pushed backwardly for removal.

It will be apparent that the dual-purpose rod provides economy in construction. In addition, the feature of interchangeable cutting element makes possible the efficient utilization of my device in dicing, slicing, cubing and otherwise cutting potatoes, cucumbers and other vegetables into pieces of various sizes and shapes. Also, this feature makes it easier to clean the device.

Other objects and advantages of my invention will become apparent from the following description, in conjunction with the annexed drawing, in which a preferred embodiment is disclosed.

In the drawings,

Fig. 1 is a side view of the device, showing the pusher plate in an intermediate position.

Fig. 2 is a front view of Fig. 1.

Fig. 3 is a section on line 3—3 of Fig. 1.

Fig. 4 is a vertical longitudinal section of the device, showing the pusher plate in its rear position, and showing the cutting element in full lines in its assembled position and in broken lines in an intermediate position while being assembled or removed.

Fig. 5 is a section on line 5—5 of Fig. 4.

Fig. 6 is a side view of the cutting element.

Upon reference to the drawings in detail, it will be seen that my improved cutting device comprises a substantially planar base 10 and a pair of longitudinal side walls 11 which are preferably respectively integral with the respective longitudinal edges of base 10. Base 10 optionally and preferably has a pair of parallel, longitudinal ridges 12 which serve as guide means for smaller vegetables which are to be moved longitudinally on base 10 for slicing.

I provide a frame for the cutting element, said frame comprising a pair of transverse frame plates 13 which are respectively connected to the inner faces of the respective side walls 11 at the front of the device. Said

2

frame plates 13 extend from above side walls 11 to a point below base 10. Each frame plate 13 has an in-turned lateral flange 14 at its lower edge, and this flange 14 is bent upwardly at its inner portion 15. Said inner portions 15 are joined by a lateral connecting plate 16 which is positioned below base 10 and above flanges 14.

Base 10 is integral at its rear edge with a depending lateral flange 17. Flange 17 is integral at its lower edge with a rearwardly extending flange 18. When the device is placed on a support such as a table or the like, flange 17 and flanges 14 rest upon the support, and base 10 is spaced from the support.

I provide a pusher element comprising a pair of parallel, transverse and longitudinal side plates 19 which are connected at their front edges by a preferably integral, transverse and lateral pusher plate 20. These side plates 19 are respectively positioned in sliding abutment with the inner faces of the side walls 11 and in sliding abutment with base 10. The lower edge of pusher plate 20 is spaced from base 10.

The upper edges of side walls 11 are respectively integral with respective in-turned, longitudinal flanges 21 which are parallel to base 10. The inner edges of flanges 21 are respectively integral with respective upstanding flanges 22. The upper edge of each side plate 19 is positioned in sliding abutment with a flange 21. The upper portion 23 of pusher plate 20 extends above side plates 19 and is of decreased width so as to be laterally spaced from flanges 22. The inner faces of flanges 22 are respectively positioned in substantial alinement with or outside the inner faces of the respective frame plates 13. The front edges of flanges 22 are respectively slightly spaced longitudinally from the rear edges of the respective frame plates 13.

It will be apparent from the above that pusher plate 20 is longitudinally slidable with respect to base 10, but that pusher plate 20 is substantially immovable transversely and laterally with respect to base 10. I provide lever means for imparting longitudinal movement to pusher plate 20.

In order to mount these lever means, I provide a rod 24 which also serves as the support for the cutting element. Rod 24 extends laterally through suitable openings in frame plates 13 and its end portions extend outside said frame plates 13. I provide two lever plates 25 which extend longitudinally and transversely and which are respectively provided intermediate their ends with suitable openings through which the respective end portions of rod 24 extend turnably. Each lever plate 25 is spaced from side wall 11 and frame plate 13 by means of a collar 26, which is mounted on rod 24 between plate 25 and plate 13. Lever plate 25 is retained on rod 24 by means of washer 27 and rod end-head 28.

The front ends of lever plates 25, as taken in Fig. 1, are respectively pivotally connected by laterally extending rivets 29 or the like to the front ends of respective link plates 30. Each link plate 30 extends longitudinally and transversely and is turnable about the axis of rivet 29. The other ends of lever plates 25 are connected to each other by lateral handle 31.

Link plates 30 are respectively pivotally connected at their rear ends to the respective side plates 19. I provide a longitudinal slot 32 in each side wall 11. Link plate 30 and side plate 19 are mounted on rivet 33 or the like, which extends laterally through slot 32. A collar 34 mounted on rivet 33 serves as a spacer for link plate 30 and side plate 19. Link plate 30 is turnable about the axis of rivet 33.

As a result of the above construction, handle 31 may be turned clockwise about the axis of rod 24, as taken in Fig. 1, in order to move pusher plate 20 rearwardly, and counterclockwise in order to move pusher plate 20 forwardly. In the extreme limit of rearward movement, collars 34 about the rear ends of the respective slots 32, and lever plates 25 extend approximately vertically. In the extreme limit of forward movement, pusher plate 20 abuts the rear edges of frame plates 13, and lever plates 25 extend approximately horizontally. The rear portions of the top edges of side walls 11 slope downwardly and rearwardly at 35 in order to provide room for the downward movement of handle 31.

Cutting element 36 comprises parallel transverse legs 37 which are formed into hooks 38 at their upper ends. These legs 37 are connected at their lower ends and also just below hooks 38 by a pair of transversely spaced, parallel, lateral arms 39. Said legs 37 and arms 39 provide a preferably square frame within which any desired cutting members may be mounted. In the embodiment shown, the cutting members take the form of transverse planar legs 40 and lateral planar arm 41, which collectively form a grill having square openings. The minor axes of said legs 40 and arms 41 extend longitudinally, so that the rear edges thereof, which may optionally be sharpened, strike an object pushed forwardly by pusher plate 20.

Each said hook 38 has a shank 42 which extends upwardly from the rear portion of the top edge of leg 37; an arm 43 which extends forwardly from shank 42 and which is transversely spaced from the top edge of leg 37; and a catch 44 which depends from arm 43 and which is transversely spaced from the top edge of leg 37 and longitudinally spaced from shank 42. Hook 38 is substantially planar. The drawings are substantially to scale of a preferred embodiment; and reference is made thereto, in particular to Figs. 2, 3, 4 and 6, for the exact shape of hook 38. While it is noted that the interior space of hook 38 is shown in Figs. 4 and 6 as substantially convex and as approximately conforming in part to the curvature of rod 24, it will be apparent that this is not essential.

Cutting element 36 is mounted on rod 24 with hook shanks 42 positioned behind rod 24, with hook arms 43 resting thereon, and with catches 44 positioned forwardly thereof. Lower arm 39 is in substantial longitudinal registry with the front edge of base 10 and is preferably slightly spaced transversely from connecting plate 16. Each side wall 11 has its front portion cut away and inturned in two places to form transversely spaced, lateral lugs 45 which are positioned in front of leg 37. As a result, cutting element 36 can turn slightly about the axis of bar 24; but the clockwise movement of element 36, as taken in Fig. 4, is stopped by lugs 45, the counterclockwise movement by the front edge of base 10. Longitudinal movement of the upper part of element 36 is substantially prevented when hooks 38 rest upon bar 24.

In order to remove cutting element 36 for cleaning or replacement, it is raised until rod 24 is positioned longitudinally opposite the respective openings between catches 44 and the top edge of upper arm 39. This opening is higher than the diameter of rod 24. The upper part of element 36 may then be pushed rearwardly until hook 38 is clear of rod 24, after which element 36 may be withdrawn transversely from the device. The removal steps may be reversed in order to re-mount element 36.

While I have disclosed a preferred embodiment of my invention and have indicated various changes, omissions

and additions which may be made therein, it will be apparent that various other changes, omissions and additions may be made without departing from the scope and spirit thereof. Reference is made to the drawing to complete the disclosure, but it will be apparent that certain of the details of construction and certain of the relative proportions and shapes of the parts may be varied to suit manufacturing convenience.

I claim:

10 In a cutting device, a frame which has a horizontal base which has a longitudinal axis, said base having up-standing side walls which also extend forwardly of said base, a lateral support rod mounted between said side walls forwardly of and above said base, a generally rectangular cutting element for mounting upon said support rod for cutting articles fed longitudinally forwardly on said base against said cutting element, means for suspending said cutting element from said rod with said cutting element extending laterally and vertically relative to said base, said suspending means comprising a pair of laterally spaced hooks having shanks extending upwardly from the top of said cutting element, said hooks also extending longitudinally rearwardly and then downwardly and being substantially of inverted J-shape, said cutting element being adapted to be suspended from said rod with the tops of said hooks extending over and in front of said rod and with said hook shanks positioned behind said rod, said cutting element then hanging freely from said rod and extending slidably between said side walls and extending in front of and below said base and being pivotable about the axis of said rod, and stop tabs extending inwardly from the respective side walls and forwardly spaced from the front edge of said base and located in front of said cutting element and serving as the forward limits to pivotable movement of said cutting element about the axis of said rod, said cutting element having sufficient freedom of longitudinal movement between the front edge of said base and said stop tabs to permit the upper end of said cutting element to be swung rearwardly and upwardly for withdrawal of said hooks from said rod and for clearance of said cutting element above said base.
